UNITED STATES PATENT OFFICE.

ALBERT HARRIES, OF NEW ROCHELLE, NEW YORK.

FEED-BAG.

No. 918,538.

Specification of Letters Patent.

Patented April 20, 1909.

Application filed December 26, 1908. Serial No. 469,456.

To all whom it may concern:

Be it known that I, ALBERT HARRIES, a citizen of the United States, and residing at New Rochelle, in the county of Westchester 5 and State of New York, have invented certain new and useful Improvements in Feed-Bags, of which the following is a specification, such as will enable those skilled in the art to which it appertains to make and use 10 the same.

This invention relates to feed bags for horses; and the object thereof is to provide an improved device of this class having a detachable ventilated bottom and improved 15 means for connecting the bag proper with said bottom whereby a new bag member may be connected with the bottom whenever desired, and a practically new bag produced at slight cost; and with this and other objects 20 in view the invention consists in a device of the class specified constructed as hereinafter described and claimed.

The invention is fully disclosed in the following specification, of which the accompanying 25 drawing forms a part, in which the separate parts of my improvement are designated by suitable reference characters in each of the views, and in which;—

Figure 1 is a side view of my improved 30 feed bag, Fig. 2 a view similar to Fig. 1 but showing the parts in a different position, and;—Fig. 3 a central vertical section of the bottom portion of the bag.

In the practice of my invention I provide 35 a flexible bag member *a* composed of canvas or any other suitable material and provided with a detachable bottom *b*. The bottom *b* is stamped or formed from sheet metal and is provided with a top flange or rim *b*² which is 40 set inwardly from the outer edge of the bottom, and the top of which is provided with a projecting annular bead *b*³ in the form of construction shown. The flange or rim *b*² is provided centrally thereof with a plurality of 45 radially projecting studs *b*⁴ which are secured therein or connected therewith in any desired manner and which are provided on their outer end portions with buttons, knobs or heads *b*⁵ which, in the construction 50 shown, are made in the form of spools, but which may be of any desired shape, and the bottom portion of the bag proper is folded upwardly so as to make said bottom portion double in thickness as shown at *a*² and to 55 form an annular flap *a*³, and that part of the bottom of said bag proper which is made

double is provided with holes, apertures or eyelets *a*⁴, and in practice the buttons, knobs or heads *b*⁵ are passed through said holes or eyelets and in this way the bottom portion 60 of the bag proper is connected with the flange or rim *b*² of the bottom *b*, and in practice I also pass around the bottom portion of the bag proper and around the flange or rim *b*² and above the buttons, knobs or heads *b*⁵ a 65 strap *c* provided at one end with buckle tongue holes, and at the other end with a buckle *c*². The strap *c* is buckled tightly around the bottom portion of the device as shown in Figs. 2 and 3, and this together 70 with the buttons, knobs or heads *b*⁵ securely holds the bag proper in connection with the bottom thereof, and in practice the annular flap *a*³ formed from the material of the bag is turned downwardly as shown in Figs. 1 and 75 3 so that it covers the strap *c* and the attaching devices by means of which the bottom portion of the bag is secured directly to the flange or rim *b*². The bottom *b* is also perforated as shown at *b*⁶, and these perforations 80 permit of the escape of dust or fine dirt from the bag, and also provide additional means for the ventilation of the bag.

With my improvement, it will be seen, that a new bag member may be connected with 85 the bottom *b* whenever desired, and as said bottom is practically indestructible, in use, a new bag may be provided at a comparatively slight expense whenever desired by simply applying a new bag member to the 90 bottom *b*.

The bag member is also provided at the top thereof with straps *d* by means of which the bag may be suspended from a horse's head in the usual manner, but any suitable 95 means may be provided for this purpose such as a headstall or any of the devices now in use.

Having fully described my invention, what I claim as new and desire to secure by Letters Patent, is;—

1. A feed bag provided with a bottom having an upwardly directed flange or rim, and a bag member detachably connected with said flange or rim by means of projecting studs 105 secured thereto and provided with buttons and corresponding holes or eyelets in the bottom of the bag member, and a strap passed around the bottom of the bag member and around said flange or rim.

2. A feed bag provided with a detachable bottom, said bottom being perforated and

- provided with an upwardly directed flange or rim having radially arranged studs provided with buttons, the bottom of the bag proper being folded upwardly so as to double the bottom portion thereof, and said double portion being provided with holes or eyelets adapted to receive said buttons, and a strap passed around the bottom portion of the bag and around the flange or rim above said 10 studs.
3. A feed bag provided with a detachable bottom, said bottom being perforated and provided with an upwardly directed flange or rim having radially arranged studs provided 15 with buttons, the bottom of the bag proper being folded upwardly so as to double the bottom portion thereof, and said double por-

tion being provided with holes or eyelets adapted to receive said buttons, and a strap passed around the bottom portion of the bag 20 and around the flange or rim above said studs, and the upwardly folded portion of the bottom of the bag proper being provided with an annular flap which is adapted to be folded downwardly over said strap and over 25 said studs and buttons.

In testimony that I claim the foregoing as my invention I have signed my name in presence of the subscribing witnesses this 24th day of December 1908.

ALBERT HARRIES
